UNITED STATES PATENT OFFICE

100,874

DESIGN FOR A BOTTLE

Albert C. Meyer, Glenshaw, Pa.

Application April 28, 1936, Serial No. 62,349

Term of patent 14 years

To all whom it may concern:

Be it known that I, Albert C. Meyer, a citizen of the United States, residing at Glenshaw, in the county of Allegheny and State of Pennsylvania, have invented a new, original, and ornamental Design for a Bottle, of which the following is a specification, reference being had to the accompanying drawing forming part thereof, in which Figure 1 is a front elevational view of a bottle showing my new design; Figure 2 a side elevational view thereof; and Figure 3 a top plan view. The opposite sides of Figures 1 and 2 are substantially the same as the ones described.

I claim:

The ornamental design for a bottle as shown and described.

ALBERT C. MEYER.
